The ornamental design for a shoe, as shown and described.

DESCRIPTION

FIG. 1 is a side view of a shoe showing my design;
 FIG. 2 is a front perspective view thereof; and,

FIG. 3 is a rear perspective view thereof.
 The even-length broken lines are directed to environment, represent unclaimed subject matter, and form no part of the claimed design.

The long-and-short broken lines form an unclaimed boundary,
 and form no part of the claim.
